DESIGN FOR A CROQUET RACK

Frank S. Chrisman, South Bend, Ind., assignor to South Bend Toy Mfg. Co., South Bend, Ind.

Application October 23, 1937, Serial No. 72,388

Term of patent 3½ years

To all whom it may concern:

Be it known that I, Frank S. Chrisman, a citizen of the United States, residing at South Bend, in the county of St. Joseph, State of Indiana, have invented a new, original, and ornamental Design for a Croquet Rack, of which the following is a specification, reference being had to the accompanying drawing, forming a part thereof.

Fig. 1 is a top plan view of the croquet rack.

Fig. 2 is a view of the croquet rack in side elevation.

Fig. 3 is a view of the croquet rack in side elevation at a 90 degree relation to Fig. 2.

Fig. 4 is a perspective view of the croquet rack on a reduced scale.

I claim:

The ornamental design for a croquet rack, substantially as shown.

FRANK S. CHRISMAN.
